UNITED STATES PATENT OFFICE.

JOSEPH HÉROUX, OF YAMACHICHE, QUEBEC, CANADA.

AUTOMATIC GAS-EXTINGUISHER.

SPECIFICATION forming part of Letters Patent No. 374,066, dated November 29, 1887.

Application filed February 9, 1887. Serial No. 227,073. (No model.)

To all whom it may concern:

Be it known that I, JOSEPH HÉROUX, a citizen of the Dominion of Canada, residing at Yamachiche, county of St. Maurice, Province of Quebec and District of Three Rivers, Canada, have invented certain new and useful Improvements in Automatic Gas-Extinguishers; and I do hereby declare that the following is a full, clear, and exact description of the same, such as will enable others skilled in the art to which it appertains to make and use the same.

My invention has reference to an automatic gas-extinguisher, having for its object the prevention of the numerous accidents arising from the ignorance or negligence of parties blowing the gas out, instead of cutting off the supply.

Figure 1 is a side elevation; Fig. 2, a plan view. Fig. 3 is a back view showing position of movable vertical piece when gas is cut off, and Fig. 4 is also a back view showing position of movable vertical piece when gas is opened.

A is an ordinary gas-bracket, to which is secured my apparatus by means of the thumb-screw B. As can be seen, the gas-flame C beats the small metallic rods D, E, and F, consequently forcing them to expand. So doing they act on the levers G H and bell-crank I in the following manner. Rod E, being joined at one end to frame J at e, and at the other end to lever H at e', pushes e' outward when it expands; but as lever H is fulcrumed at h and h' e' is shorter than h' f, end f moves inward a greater distance than e' moves outward. On the other hand, as rod F is joined at f to lever H and at f' to lever G, end f' also moves outward, for it is not only forced to do so by the expansion of E acting on lever H, but also by the expansion of rod F, so that end f' moves outward a greater distance than the sum of the expansions of rods E and F, on account of the unequal leverage of H. Now, lever G is fulcrumed at g, and as f' g is shorter than g d, d moves inward a greater distance than f' moves outward, and as rod D joins lever G at d and bell-crank I at d' the distance that end d' will move outward will be equal to the distance that end d moves inward plus the expansion of rod D. Now, if we consider bell-crank I, it will be seen that arm d' i is shorter than arm i' i; consequently i' will move downward a greater distance than d' will move out-

ward. However, d' i could be made equal to i' i if i' moved downward a sufficient distance by so doing. If the light is now extinguished, 55 the rods D, E, and F would lose their heat, consequently contract, and the exact opposite effects would take place—that is, the end i' of bell-crank I would rise instead of move downward. Now, as can be seen in Fig. 1, the 60 gas-stopper L is provided with a spiral spring, M, placed on its stem. This spring is attached at one end at m to bracket A and at the other at l to stem of stopper L, so that when L is in position shown in Figs. 1 and 4 the spring M 65 tends to bring stopper L in position shown in Fig. 3—that is, to cut off the supply of gas. To keep stopper L in position shown in Figs. 1 and 4 it is provided with an arm, N, having a small slot, n, in its outer end. This little slot 70 n serves to receive end o of movable vertical piece O, thereby keeping stopper L open. As can be seen by examining Figs. 3 and 4, end o of vertical piece O passes through an aperture in frame J, (shown in dotted lines,) which is 75 smaller at the top than at the bottom, so that when end o passes through slot n to hold stopper L open, the latter, tending to close under the influence of spring M, forces portion P of O against end i' of bell-crank I, so that when end 80 i' is going down, under the influence of the expansion of rods D, E, and F, there comes a moment when it passes beyond check p, and as O is pressing against i' vertical piece O takes position shown in Fig. 4. Now, when 85 the contraction takes place, end i' rises and lifts vertical piece O, so that there comes a moment when o rises out of slot n, and at the same time stopper L closes immediately, arm N being no more kept in position by end o, at 90 the same time vertical piece O, being no longer pressed against i', is thrown back in position shown in Fig. 3 by means of spring W, which takes its point of support on yoke V, which also serves to keep O in position. Vertical piece 95 O being thrown off, end i' falls by its own weight until it is kept up by check v, and is now ready again to keep arm N in position. O is made of two pieces kept together by means of screws x and y, and is provided with the slot X, so as 100 to adjust it to its right length. Gas-bracket A is also provided with stopper Y, so that the light may be moderated at will. Now, it can easily be seen that if the gas is blown out, in-

stead of being cut off, the rods D, E, and F will contract, and consequently stopper L will cut off the supply of gas automatically. Of course when gas is lighted arm N has to be drawn back and hooked on end o, so as to keep stopper L open. The gas may also be cut off and turned by means of stopper Y; but in any case stopper L will always have to be opened.

Having described my invention, what I claim, 10 and desire to secure by Letters Patent, is—

The combination, with a frame, J, provided with levers H and G and metallic rods D, E,

and F, of a vertical support provided with yoke V, a bell-crank, I, a rod, O, and means for attaching said parts to a gas-bracket, and 15 the gas-cock provided with spring M and arm N, all constructed substantially as described and shown.

In testimony whereof I have affixed my signature in presence of two subscribed witnesses. 20

JOSEPH HÉROUX.
